UNITED STATES PATENT OFFICE.

EPHRAIM PARKER, OF ROCK ISLAND CITY, ILLINOIS, ASSIGNOR TO ALFRED A. PARKER.

IMPROVEMENT IN MACHINES FOR PRESSING TOBACCO.

Specification forming part of Letters Patent No. 8,909, dated April 27, 1852.

To all whom it may concern:

Be it known that I, EPHRAIM PARKER, of Rock Island, county of Rock Island, and State of Illinois, (assignor to ALFRED A. PARKER, of St. Louis, in the county of St. Louis and State of Missouri,) have invented a new and useful Machine for Pressing, Flattening, and Shaping Tobacco into Plugs of Commerce; and I do hereby declare the following to be a full, clear, and exact description thereof, reference being had to the accompanying drawings, and letters marked thereon, forming a part of this specification.

I have been for several years engaged in endeavoring to construct a machine capable of flattening, shaping, and pressing tobacco into plugs such as those of commerce, so as to obviate the great difficulties existing to a practicable application of machinery to that purpose, which I have at last accomplished, the efficacy of which I have proved by actual experiment upon a large scale. The great obstacles heretofore existing in the way of performing this operation by machinery have been the difficulty of keeping the sinkers or pressers and the cells or molds in which the tobacco is pressed free from the gum and licorice of the tobacco, and preventing the plugs, after leaving the molds, from swelling out of shape, which they will do immediately after being released from pressure, all devices for these purposes heretofore used being found too complicated, liable to get out of order, and altogether impracticable.

In the accompanying drawings, Figure 1 is a side elevation of my machine, with portions of the frame and wheels broken off to show important parts which would otherwise be hid; Fig. 2, an end view, Fig. 3 a top or plan view, and Fig. 4 a section through the conductor, a portion of the disk 3 and discharger 12, in each of which when the same parts are shown they are designated by the same letters of reference.

2 is the frame, resting on pieces of timber which support and sustain the moving machinery, which may be made of iron or other suitable material; 3, a revolving disk in which the molds or cells are cut, and it can be made large

enough to contain four or any desired number of them of iron, and the molds lined with steel or the whole disk formed of chilled or case-hardened metal. The molds or cells are cut through the disks, and the bottoms of them are formed by a revolving bed-plate, 4, the periphery of which is formed into cogs which mesh into a pinion on the disk communicating the desired motion to it, and it is provided with a steel scraper, 5, screwed to one side of the frame, and a cloth-roller, 6, revolving in a frame working on the other side of the frame. This roller is kept saturated with oil by occasionally replenishing it with a saturated sponge, or an oil-box can be constructed over it, and follows after the scraper to oil the surface of the bed-plate. The bed-plate revolves at such a rate as to present a clean and oiled bottom to every mold or cell, at each pressing the gum, licorice, &c., of the tobacco being scraped off by said scraper 5, and the surface of the bed (which as it revolves becomes the bottom of the mold) is kept moistened with oil by said cloth roller 6. Thus a clean and oiled bottom is formed to the molds at each pressing. The pressure is attained by means of double toggle-levers 7, connected to the driving-shaft by the pitman 8. In order to keep the sinkers 9 clean and free from the gum, &c., of the tobacco, I form them, four or more in number, on a shaft operated upon by suitable mechanism in such a manner, hereinafter described, that they shall revolve after every eight pressings, so as to present a new sinker; and I provide a pan, 10, underneath the sinkers, in which I put a liquid which will dissolve the gum, and above the sinkers I provide a cushion, 11, which is kept oiled, and so placed as to fall on the face of the sinkers as they revolve, for the purpose of wiping them clean and at the same time oiling them. The plugs, after being pressed, are forced from the molds by means of a discharger, 12, each side and edges of which, and directly in the rear of the face of it, in recesses, I place cloth or other soft substance, which is kept saturated with oil for the purpose of oiling and cleaning the sides and ends of the molds. The discharger is operated upon at the proper moment by a pit-

man connected with the wheel 13, meshing in the main driving-wheel; or it may be connected directly with the main driving-shaft for the purpose of forcing the pressed plugs between two endless belts or aprons, 14, forming a conductor. These aprons are placed close enough together, and I intend to have them much longer than represented in the drawings, so as to compress and keep the tobacco for a long time in that compressed state until it becomes permanently consolidated, which prevents it from expanding when discharged from the conductor.

For feeding the machine, I provide a box or hopper, 15, which may be any desired height and a trifle larger each way than the size of the plug before being pressed, so that the plugs can be thrown in one upon top of the other. The plugs thus placed in the hopper are forced out endwise by a sliding feeder, 16, attached by a joint to a bent rod, 17, which is operated upon alternately by a pin, 8', on the pitman 8, and a spring, 18, on the top of the frame. The pin 8' raises the rod, drawing the feeder in, and the spring 18 throws it back again. This feeder forces the plug into the trough 19, and from thence it is forced into the mold by another sliding feeder, 20, connected with the end of the pitman 8 by the rod 21. Thus, by two feeders sliding at right angles to each other, the plugs one after the other are removed from the bottom of the pile in the hopper and supplied to the molds as the disk revolves with perfect regularity and precision. The desired rotary motion is given to the disk 3 by the cam 22 on the main driving-shaft impinging against a cam or star-wheel, 23, which is attached to a shaft having a bevel cog-wheel meshing into another bevel cog-wheel on the shaft attached to the disk, which rotates it sufficiently to bring a mold opposite to the sinkers, where it is retained in that position by its own friction until the sinkers have done their work. The sinkers are moved one-quarter of a revolution at every eight pressings by the following mechanism: On the inside of the frame I have a ratchet-wheel, 24, with eight teeth, on which I have a cam formed by a small tangent cut on the circle, and jointed to the sinker-bar 25. I have a pawl, 26, for the purpose of acting against the teeth of the ratchet-wheel 24, so as to move it one tooth at each pressing. On the end of the frame I have a lever, 27, to the ends of which is jointed two rods or hands, 28 29, one of which, 29, is long enough to reach a little beyond the sinker-bar and rests on the cam of the ratchet-wheel 24, and it is provided with two pins, 30 30', projecting downward near its end, and the other arm, 28, terminating in the form of a ratchet for the purpose of operating upon the shaft. On one end of the sinker-shaft is a ratchet-wheel, 31, with four ratchet-teeth attached to the sinker-bar. 32 is a stiff spring, which has a catch at its end, so as to fall into a notch cut in the shaft of

the sinkers, for the purpose of retaining the sinker-shaft in one position while pressing. Now, when the sinker has pressed eight times, the ratchet-wheel 24 will have advanced by the action of the pawl one revolution, which will bring the flat side of the cam of the ratchet-wheel 24 on top, which allows the arm 29 to fall, so that the sinker-bar will be clamped by the two pins 30 30', and the arm 29 will be impelled by the sinker-bar, which will impel the arm 28, the ratchet on the end of which will enter under the spring 32 and raise it out of the notch and at the same time act on the teeth of the ratchet-wheel on the shaft of the sinkers, so as to revolve them one-quarter of a revolution.

The dimensions of the machine will of course be varied according to the size of the plug to be pressed, and the disk can be made to contain any number of molds. The power is applied to the main driving-pulley 33 by a belt, cog-gearing, or in any other way. It is fed with tobacco through the hopper by a hand, which can at the same time attend to the roller-cushion for the sinkers and those on the discharger and keep them properly supplied with oil. The conductor which receives the tobacco after leaving the mold is a very important feature in my invention, which, as before said, is designed to retain the pressure upon the lumps until they have become thoroughly consolidated so as to prevent them from swelling and loosing the size and shape in which it is desirable to preserve them. The endless belts or aprons I have found to answer the purpose well; but I have other plans which would answer the purpose. The plugs are forced into the conductor by the discharger between the belts, the lumps adhere to them and carry them forward, and the conductor is constantly kept full, each plug as it leaves the molds forcing the mass of plugs forward, dropping one plug out at the opposite end of the conductor at each pressing.

I would here observe that my machine with a few additions and modifications can be admirably well adapted for the purpose of pressing brick with dry clay, and I intend constructing a machine for the purpose.

Having thus fully described the nature, construction and operation of my improved tobacco-press, what I claim therein as new, and desire to secure by Letters Patent, is—

1. The use of the revolving mold-disk 3, combined, with its revolving bed-plate 4, with the scraper 5 and cloth-roller 6, or their equivalents, for keeping the molds free from the licorice or juice of the tobacco, substantially as described.

2. The use of revolving sinkers 9, constructed substantially as described, combined with the pan 10 and cushion 11, or their equivalents, for keeping the same clean, and the combination therewith of mechanism for moving the sinkers a quarter of a revolution at

every eight, more or less, number of pressings, substantially as described.

3. The conductor formed of endless aprons or belts, or their equivalents, for confining and retaining the plugs under pressure until they are thoroughly consolidated in manner and for the purpose substantially set forth.

In testimony whereof I have hereunto signed my name before two subscribing witnesses.

EPHRAIM PARKER.
